UNITED STATES PATENT OFFICE.

GUSTAF LIBERT REENSTIerna, OF BOSTON, MASSACHUSETTS, ASSIGNOR
TO JOHN L. FISKE AND ARTHUR K. SMITH, OF CAMBRIDGE, MASSA-
CHUSETTS.

LOCK-HINGE.

SPECIFICATION forming part of Letters Patent No. 584,239, dated June 8, 1897.

Application filed September 14, 1896. Serial No. 605,704. (No model.)

To all whom it may concern:

Be it known that I, GUSTAF LIBERT REEN-
STIerna, a citizen of the United States, and a
resident of Boston, in the county of Suffolk and
5 State of Massachusetts, have invented new
and useful Improvements in Lock-Hinges, of
which the following, taken in connection with
the accompanying drawings, is a specification.

This invention relates to improvements in
10 lock-hinges for blinds or shutters for windows,
&c., and it is carried out as follows, reference
being had to the accompanying drawings,
wherein—

Figure 1 represents an outside elevation of
15 a blind or shutter provided with my improved
lock-hinge. Fig. 2 represents a partial interior
view of the same. Fig. 3 represents an
enlarged cross-section on the line 3 3, shown
in Fig. 1. Fig. 4 represents a vertical section
20 on the line 4 4, shown in Fig. 3. Fig. 5 represents
a front view of the lock-hinge, partly
shown in section. Fig. 6 represents a bottom
plan view of the upper member of the hinge.
Fig. 7 represents a top plan view of the lower
25 member of the hinge; and Fig. 8 represents a
detail perspective view of the releasing cam or
lever for unlocking the hinge preparatory
to swinging the blind or shutter from closed
to open position, or vice versa.

30 Similar letters refer to similar parts wherever they occur on the different parts of the drawings.

In the drawings, A represents a window-frame, and B represents a blind or shutter
35 hinged thereto by means of my improved
lock-hinge, as will hereinafter be more fully
shown and described.

My improved lock-hinge consists of a lower
member C, secured to the window-frame A
40 and provided with upwardly-projecting tapering
teeth or cogs C', adapted to interlock with
corresponding teeth or cogs D' on the
member D, secured to the blind or shutter B,
as shown in the drawings.

45 The teeth or cogs C' and D' are arranged in-
ward a slight distance from the outer periph-
ery of the disks, so as to provide a free unob-
structed trackway for the cam of the operating
or releasing lever, presently to be described.

50 To the member C is secured a vertical pivot-
pin C'', which is loosely journaled in a verti-

cal cylindrical recess in the member D, as
shown in Fig. 4.

The upper end of the blind or shutter may
be provided with a similar lock-hinge; but in 55
practice any well-known hinges may be used
at the upper end of the blind or shutter, as
shown at E F in Fig. 1.

In practice I prefer to make the interlock-
ing teeth C' D' on the parts C D tapering, as 60
shown in Figs. 4 and 5, so as to insure a more
positive lock between said parts when said
toothed parts are interlocked and thus pre-
vent rattling.

In connection with this my improved lock- 65
hinge I use a releasing device which is com-
posed of a spindle G, journaled in a recess or
bearing in the blind or shutter B and pro-
vided at its outer end with a suitable cam or
crank projection g, located between the disks 70
C D, as shown in Figs. 3 and 4.

The spindle G is provided with a suitable
handle G', by means of which it may be
turned for the purpose of raising the blind B
sufficiently to cause the toothed members C 75
D to be disengaged from each other whenever
it is desired to open or close the blind or ad-
just its position.

By raising the handle or lever G' the crank
or cam projection g is brought in contact with 80
the upper surface of the lower disk C, thus
causing the blind B and its locking-disk D to
be raised sufficiently to unlock the said disk D
from the lower stationary disk C, after which
the blind may be swung to any desired posi- 85
tion and locked simply by letting go the hold
on the handle G', when the blind will descend
by gravity, so as to cause the toothed mem-
bers C D to be interlocked.

It is to be observed that the releasing-spin- 90
dle G is journaled in the blind itself and has
its operating-handle G' projecting through a
slot formed therein. With this construction
the said releasing device is in easy access and
can be readily operated from within.

95 It will be noticed that in this my device I
make use of no springs for holding the toothed
members C D in interlocked positions, as in
my device such is accomplished by gravity
only.

100 In practice I prefer to provide the upper
disk D with a peripheral flange D'', which

serves as a shield for preventing dust, dirt, snow, or rain from getting in between the teeth of the disks C and D, as shown in Figs. 1, 4, 5, and 6.

5. What I wish to secure by Letters Patent and claim is—

The herein-described lock-hinge, consisting of a pair of disks having teeth upon their approaching faces, said teeth being arranged inward away from the outer edges of the disks, one of said disks being secured to a window-frame or the like and the other disk secured to a blind or the like, and a releasing device for said hinge consisting of a spindle journaled on the said blind or the like on a line with the lower disk and having a cam at one

end which is arranged to have a partial rotation between the faces of said disks, near the edges thereof and to bear upon the upper face of the lower disk, and an operating-handle having one end fixed to said spindle and its other end projecting outward from the blind, substantially as described.

In testimony whereof I have signed my name to this specification, in the presence of 25 two subscribing witnesses, on this 8th day of September, A. D. 1896.

GUSTAF LIBERT REENSTIerna.
